UNITED STATES PATENT OFFICE.

ARTHUR S. KNIGHT, OF NEWARK, NEW JERSEY, ASSIGNOR TO WESTINGHOUSE LAMP COMPANY, A CORPORATION OF PENNSYLVANIA.

SUPPORT FOR INCANDESCENT-LAMP FILAMENTS.

1,125,121.

Specification of Letters Patent. Patented Jan. 19, 1915.

Application filed July 19, 1909, Serial No. 503,542. Renewed May 14, 1912. Serial No. 697,303.

To all whom it may concern:

Be it known that I, ARTHUR S. KNIGHT, a subject of the King of Great Britain, and a resident of Newark, in the county of Essex 5 and State of New Jersey, have invented a new and useful Improvement in Supports for Incandescent-Lamp Filaments, of which the following is a specification.

My invention relates to electric incandescent lamps and particularly to tubular lamps having straight filaments extending from end to end thereof.

The object of the invention is to provide a lamp of the character indicated that shall embody simple and effective means for maintaining the filament taut and approximately central within the casing.

The use, in incandescent lamps, of very long tungsten, molybdenum or similar metallic filaments which become pliable and sag under their own weights upon being heated to incandescence, requires the provision, in such lamps, of means which will maintain the filaments taut under all conditions, and, at the same time, will permit of ready expansion and contraction of the filaments without subjection to undue strains. The desired results may be secured, in a tubular lamp, by dividing the filament into sections and placing suitable tension devices between adjacent sections. The present invention provides an especially advantageous means for performing the desired function and also for supporting the filament approximately central within, and out of engagement with, the tubular casing.

Figure 1 of the accompanying drawing is a side view of a lamp embodying my invention. Fig. 2 is a side view of the tension device used in the lamp of Fig. 1. Figs. 3 and 5 are side views of lamps embodying modifications of the lamp of Fig. 1, Figs. 4 and 6 are perspective views of the tension devices used in the lamps of Figs. 3 and 5, respectively. Figs. 7 and 8 are, respectively, side and edgewise views of a modified form of tension device.

Stretched between the ends of a tubular glass casing or bulb 1, and arranged in series relation therein, are a plurality of filament sections 2 and 3, interposed and connected between which is a supporting and tension device 4 that comprises a ring-shaped body portion 5 and inwardly extending and substantially radial end por-

tions 6 and 7 having eyes at their extremities that are connected to the filament sections and are bent to extend along and in the direction of the axis of the lamp.

The tension device is preferably composed 60 of nickel or other suitable resilient material, and the ring-shaped body portion thereof, which conforms substantially to and loosely fits the interior of the casing, is flattened in order to improve its resiliency. The ring-shaped body portion serves also as means for supporting the filament out of engagement with the sides of the casing and for maintaining it approximately central 65 therein.

Because most materials possessing sufficient resilience to adapt them for use in construction of the tension device of Fig. 1 are also of high specific resistance, the device shown in Fig. 1 may not be found suitable 75 where a low-resistance connection between the filament sections is desirable or necessary.

In Figs. 3 and 4 is shown a tension device consisting of a member 4^a, that is of 80 substantially the same form as that shown in Fig. 1 and composed of copper or other material of high conductivity, and a resilient member or spring 8 connected between the end portions of the member 4^a.

The resilient member or spring 8 consists of a reversely bent strip of material of substantially the form of the letter S, the extremities of which are provided with hooks 9 for attaching the same to eyes 10 in the 90 end portions of the member 4^a.

In Figs. 5 and 6 the resilient member is in the form of a helical spring 11, which permits of a greater range of expansion and contraction than the S-shaped device of 95 Figs. 3 and 4.

Figs. 7 and 8 illustrate a modification of the form of the tension device, shown in Figs. 1 and 2, the annular portion 4^b thereof being flattened into oblong form in cross section. This form of the device is more flexible and is otherwise more suitable for use in some instances than the device of Figs. 1 and 2.

I claim as my invention:

1. A combined support and connector for alined filament sections in a tubular incandescent electric lamp comprising a member having a ring shaped body portion fitting the interior of the lamp tube, and inwardly

105

110

extending end portions that are respectively connected to adjacent filament sections.

2. A combined support and connector for aligned filament sections in a tubular incandescent electric lamp comprising a member having a ring shaped body portion fitting the interior of the lamp tube, inwardly extending end portions that are respectively connected to adjacent filament sections, and

10 a resilient member interposed between the end portions of the said member.

3. A combined support and connector for aligned filament sections in a tubular incandescent electric lamp comprising a member

15 composed of low-resistance material, having a ring shaped body portion fitting the interior of the lamp tube, inwardly extending

end portions that are respectively connected to adjacent filament sections, and a resilient member interposed between the end portions 20 of the said member.

4. A combined support and connector for aligned filament sections in a tubular incandescent electric lamp comprising a member having a ring shaped body portion and 25 crossed inwardly extending end portions.

In testimony whereof, I have hereunto subscribed my name this 7th day of July, 1909.

ARTHUR S. KNIGHT.
